[57] ABSTRACT

The existing hydrocarbon content in the recycle acid in an alkylation unit is determined. Changes in earnings associated with increasing and decreasing the hydrocarbon content conditions are also determined. The interface level separating the acid phase and the hydrocarbon phase in an acid settler in the alkylation unit is controlled in accordance with the determinations to achieve and maintain a desired hydrocarbon content for the recycle acid.

FIG. 13 **MEANS AND METHOD FOR CONTROLLING
ALKYLATION UNIT TO ACHIEVE AND MAINTAIN
A DESIRED HYDROCARBON CONTENT FOR
RECYCLE ACID**

BACKGROUND OF THE INVENTION

1. Field of the Invention

The present invention relates to control systems in general and, more particularly, to a control system and method for an alkylation unit.

2. Description of the Prior Art

Heretofore, systems controlling the hydrocarbon content of recycle acid in an alkylation unit were used to maintain a predetermined hydrocarbon content. Such a system is described and disclosed in U.S. Pat. application Ser. No. 281,063, filed Aug. 16, 1973 assigned to Texaco Inc., assignee of the present invention.

The present invention distinguishes over the aforementioned in selecting a desired hydrocarbon content for the recycle acid, based on economic factors, and maintaining the hydrocarbon content at the desired value.

SUMMARY OF THE INVENTION

A system controls an alkylation unit so as to achieve a desired hydrocarbon content for recycle acid in the alkylation unit. The alkylation unit includes a contactor wherein olefins and isoparaffin entering the contactor are reacted in the presence of acid. The contactor provides an acid-hydrocarbon mixture to a settler which separates the acid to provide a hydrocarbon product, including alkylate, and hydrocarbon enriched acid. A portion of the enriched acid is discharged and is replaced by fresh acid. The replenished enriched acid is recycled to the contactor. The control system controls one flow rate of fresh acid and discharge acid flow rate relatively to the other flow rate in accordance with a control signal. Characteristics of the olefin-isoparaffin charge stream, the fresh acid, the recycle acid and the hydrocarbon product are sensed by sensing circuits which provide signals corresponding to the sensed characteristics. Other devices sense the flow rates of the olefin-isoparaffin charge stream, the recycle acid, the discharge acid and the hydrocarbon product and provide corresponding signals. The interface levels between the hydrocarbon phase and the acid phase in the settler is also sensed by a circuit which provides a corresponding signal. Signals are provided which correspond to economic values related to the octane rating of the alkylate and the cost of the acid. A control signal circuit provides the control signal in accordance with the sensed characteristic signals, the sensed flow rate signals, the sensed level signal and the economic signals to provide the control signal thereby controlling the one acid flow rate so as to control the interface level to achieve the desired hydrocarbon content in the recycle acid.

The objects and advantages of the invention will appear more fully hereinafter, from a consideration of the detailed description which follows, taken together with the accompanying drawings wherein two embodiments are illustrated by way of example. It is to be expressly understood, however, that the drawings are for illustrative purposes only and are not to be construed as defining the limits of the invention.

DESCRIPTION OF THE DRAWINGS

FIG. 1 shows a simplified block diagram of a control system, constructed in accordance with the present invention, for controlling an alkylation unit which is also shown in partial schematic form.

FIGS. 2 through 12 are detailed block diagrams of the H_B computer, the programmer, the olefin signal means, the H_C computer, the ΔEA computer, the S computer, the G computer, the F_S computer, F_H computer, the H_T signal means and the set point signal means shown in FIG. 1.

FIG. 13 is a simplified block diagram of a control system, constructed in accordance with the present invention, using a general purpose digital computer.

DESCRIPTION OF THE INVENTION

Referring to FIG. 1, there is shown a portion of an alkylation unit in which an olefin is reacted with isoparaffin at a predetermined temperature and in the presence of a catalyst, such as sulfuric acid and which is herein-after referred to as the reaction acid, to form a higher molecular weight isoparaffin. For purpose of explanation, the acid in the following description shall be sulfuric acid. The olefin may be butylenes, propylene or a mixture of butylenes and propylene, while the isoparaffin may be isobutane.

The olefins and isoparaffin enter a contactor 4 by way of a line 6, where the olefins and isoparaffin are contacted with the acid entering by way of a line 7. Contactor 4 provides an acid-hydrocarbon mix by way of a line 8 to an acid settler 12. Settler 12 separates the hydrocarbon product from the acid. The hydrocarbon product, which includes alkylate, is removed through a line 14 for further processing while the acid is removed by way of a line 16 for recycling. It should be noted that the acid from settler 12 is enriched with hydrocarbon which has not been separated by the action of settler 12. Acid settler 12 may be the only acid settler in the unit or it may be the last acid settler of a group of acid settlers.

Fresh acid enters line 16 by way of a line 17 as needed to maintain a desired recycle acid strength. A pump 20 pumps the recycle acid from line 16 into line 7. A portion of the recycle acid in line 7 is discharged by way of a line 21. The discharge acid may be provided to another alkylation unit or disposed of.

The hydrocarbon content of the recycle acid is controlled in a manner so as to achieve a desired hydrocarbon content for the recycle acid. The interface level controls the hydrocarbon content of the recycle acid. The level of the interface of the acid phase and the hydrocarbon phase in settler 12 is controlled by controlling the fresh acid entering line 17 and the discharged acid leaving line 21. As shown, the fresh acid is controlled directly as a function of the interface level. Thus if the fresh acid flow rate is increased the acid interface level would increase since the discharge acid flow rate is not being changed. Conversely if the fresh acid flow rate is decreased, the interface level decreases. It would be obvious to one skilled in the art that the discharge acid flow rate could be controlled as a function of the interface level while maintaining the fresh acid flow rate.

The discharge acid flow rate is maintained at a predetermined rate by a flow recorder controller 24, a valve 25 and a flow rate sensor 26. The set point of flow con-

troller 24 is set to a predetermined flow rate. Sensor 26 provides a signal E_1 corresponding to the discharge acid flow rate R_{AB} . Controller 24 senses the difference between the existing flow rate and the position of the set point and controls valve 25 accordingly so that the flow rate of the discharge acid in line 21 assumes the predetermined flow rate.

A conventional type level sensor 30 detects the interface level in settler 12 and provides a signal E_2 , corresponding to the sensed level, to a level recorder controller 34. The set point in level recorder controller 34 is positioned in a manner as hereinafter described. Controller 34 provides a signal to a valve 36, for controlling the flow rate of fresh acid in line 17, in accordance with the position of the set point of level recorder controller 34 and the sensed interface level to control the interface level as heretofore described.

The hydrocarbon content of the recycle acid may be controlled so as to achieve an optimum operating condition as can be seen from the following equations:

$$\Delta EA = (\Delta Q)(W_Q) - (\Delta A)(W_A)$$

where ΔEA is a change in earnings, ΔQ is the differential octane rating of the alkylate product resulting from changes in the recycle acid hydrocarbon content, W_Q is the worth of a unit change in octane rating in dollars per octane per barrel of alkylate, ΔA is the differential acid consumption resulting from changes in the recycle acid hydrocarbon content in tons per barrel of alkylate, W_A is the cost of acid in dollars per ton.

$$\Delta Q = G_C - G_B$$

where G_B is a quantity calculated at the existing recycle acid hydrocarbon content H_B , and G_C is the quantity calculated at any other recycle acid hydrocarbon content H_C .

H_B is the existing recycle acid hydrocarbon content in volume percent and is calculated from the following equation:

$$H_B = 100(D_A - D_B)/D_A - D_H$$

where D_A , D_H and D_B are the densities of the acid portion of the recycle acid, of the hydrocarbon portion of the recycle acid and of the recycle acid.

$$G_C = a_1 S_C^2 + a_2 P_R H_C$$

$$G_B = a_1 S_B^2 + a_2 P_R H_B$$

where a_1 and a_2 are constants which by way of example may have values of -6.5 and 0.068, respectively.

For the condition that $P_R \geq P_U$, $P_R = 1.0$

For the condition that $P_R < P_U$, $P_R = P_B/P_U$

where P_B is the ratio of propylene to the total olefins in the olefins-isoparaffin charge stream and P_U is a predetermined upper limit for the propylene-olefins ratio and may have a value of 0.6

$$S_B = [100R_O(R_R + R_H)]/[C_V R_R(100 - H_B)]$$

$$S_C = [100R_O(R_R + R_H)]/[C_V R_R(100 - H_C)]$$

where R_O is the rate of flow of olefins charged to contactor 4 in barrels per hour, R_R is the rate of flow of the recycle acid in barrels per hour, R_H is the rate of flow of the hydrocarbon product in barrels per hour, C_V is the internal volume of contactor 4 in barrels.

$$\Delta A = A_B[(F_{SC} F_{HB}/F_{SB} F_{HC}) - 1]$$

where A_B is the existing acid consumption in tons per barrel of alkylate; F_{HB} and F_{SB} are quantities calculated at the existing recycle acid hydrocarbon content H_B , F_{HC} and F_{SC} are quantities calculated at any other recycle acid hydrocarbon content H_C .

$$A_B = b R_{AB}/P_K R_H$$

where R_{AB} is the existing discharge acid rate of flow in barrels per hour, R_H is the flow rate of the hydrocarbon product in barrels per hour, P_K is the volume fraction of alkylate product in the hydrocarbon product, b is a conversion factor for converting barrels per hour to tons per hour and is dependent on the type of acid. By way of example, the factor b may have a value of 0.3212 for sulfuric acid.

For the condition $H_B \geq H_M$

$$F_{HB} = C_1$$

For the condition $H_B < H_M$

$$F_{HB} = C_2 + C_3[(H_B - H_R)/100] + C_4[(H_B - H_R)/100]^2 + C_5[(H_B - H_R)/100]^3$$

For the condition $H_C \geq H_M$

$$F_{HC} = C_1$$

For the condition $H_C < H_M$

$$F_{HC} = C_2 + C_3[(H_C - H_R)/100] + C_4[(H_C - H_R)/100]^2 + C_5[(H_C - H_R)/100]^3$$

where H_M is an upper limit for the recycle acid hydrocarbon content, H_R is a reference hydrocarbon content value for the recycle acid and may have a value of 30, and C_1 through C_5 are constants and by way of example for a particular alkylation unit may have values of 1.25,

1.0, 2.087406, -0.83735672 and -10.482274, respectively.

16.

$$F_{SB} = \exp \left\{ S_B^2 \left[d_1 \left(\frac{P_B}{1-P_B} \right) + d_2 \left(\frac{P_B}{1-P_B} \right)^2 + d_3 \left(\frac{P_B}{1-P_B} \right)^3 + d_4 \left(\frac{P_B}{1-P_B} \right)^4 \right] \right\}$$

17.

$$F_{SC} = \exp \left\{ S_C^2 \left[d_1 \left(\frac{P_B}{1-P_B} \right) + d_2 \left(\frac{P_B}{1-P_B} \right)^2 + d_3 \left(\frac{P_B}{1-P_B} \right)^3 + d_4 \left(\frac{P_B}{1-P_B} \right)^4 \right] \right\}$$

where d_1 through d_4 are constants associated with a particular alkylation unit. For one such unit, d_1 through d_4 may have values of 0.942361, -0.18270208, 0.023882011 and -0.0012078644, respectively.

$$H_{C1} = H_B + \Delta H$$

$$H_{C2} = H_B - \Delta H$$

where H_{C1} and H_{C2} are increased and decreased, respectively, hydrocarbon contents for the recycle acid and ΔH is a predetermined change for the recycle acid hydrocarbon content.

For control purposes when

$$H_{C1} > H_{CL}, H_{C1} = H_B$$

$$H_{C2} < H_{CU}, H_{C2} = H_B$$

where H_{CU} and H_{CL} are upper and lower limits, respectively, for the controlled hydrocarbon content of the recycle acid.

Sensors 40, 40A and 40B are conventional type sensors sensing the flow rate R_T of the olefins and isoparaffins in line 6, the flow rate R_R of the recycle acid in line 7, and the flow rate R_H of the hydrocarbon product in line 14, respectively, and providing signals E_3 , E_4 and E_5 , respectively.

Density analyzers 43, 43A and 43B sample the recycle acid, the fresh acid and the hydrocarbon product and provide signals E_6 , E_7 and E_8 , respectively, corresponding to the densities D_B , D_A and D_H , to an H_B computer 45.

H_B computer 45 provides a signal E_9 corresponding to the hydrocarbon content H_B of the recycle acid in accordance with signals E_6 , E_7 and E_8 and equation 3. Referring also to FIG. 2, signals E_6 , E_8 are subtracted from signal E_7 by subtracting means 48 and 48A, respectively, to provide signals to a divider 49. Divider 49 divides the signal provided by subtracting means 48 with the signal from subtracting means 48A to provide a signal to a multiplier 50. Multiplier 50 multiplies the signal from divider 49 with a direct current voltage V_1

corresponding to the term 100 in equation 3 to provide signal E_9 .

Referring again to FIG. 1, signals corresponding to the ratio P_B of propylene to olefins and to the ratio of olefins to the total constituents in line 6 are developed as follows. Chromatograph means 55 samples the olefins and isoparaffin stream in line 6 in response to a reset pulse E_{10} from a programmer 58. Chromatograph means 55 in turn provides a continuous type signal E_{11} to olefin signal means 60 and a pulse signal E_{12} to programmer 58.

Referring now to FIG. 3, the control sequence is initiated by an operator who activates an "on-off" switch 63 in programmer 58 to pass a direct current voltage V_1 to clock means 64. Clock means 64, when energized by voltage V_2 , provides a pulse E_{13} whose trailing edge triggers a one-shot multivibrator 67. The duration of time between pulses E_{13} is such as to allow the system to stabilize after each calculation. Multivibrator 67 provides reset pulse E_{10} , which in turn triggers another one-shot multivibrator 68. When triggered multivibrator 68 provides a pulse E_{14} whose function will be explained hereinafter.

The pulse signal E_{12} from chromatograph means 55 is applied to a control pulse circuit 74. Control pulse circuit 74 is the same as control pulse circuit 43 described in U.S. application Ser. No. 257,408. Control pulse circuit 74 provides control pulses E_A through E_J . Pulse E_J is also provided to a one-shot multivibrator 75 which operates as a time delay. The trailing edge of the pulse provided by the triggering of multivibrator 75 triggers another one-shot multivibrator 76. Multivibrator 76, when triggered, provides a pulse E_K . A counter in control pulse circuit 74 is reset by reset pulse E_{10} .

Referring now to FIG. 4, control pulses E_A through E_J coincide with peaks of signal E_{11} corresponding to the different constituents of the olefin-isoparaffin stream in line 6. Each control pulse of pulses E_A through E_J controls a corresponding sample and hold circuit of sample and hold circuits 80 through 80I, respectively, to sample and hold a particular peak of signal E_{11} . The following table relates a particular sample and hold circuit to a corresponding constituent.

Circuit	Constituent	Circuit	Constituent
80	Ethane	80E	Normal pentane
80A	Propane	80F	Propylene
80B	Iso-butane	80G	Butylenes
80C	Normal butane	80H	Pentylenes
50 80D	Iso-pentane	80I	All olefinic compounds with 6 or more carbon atoms

Multipliers 84 through 84I multiply the outputs from sample and hold circuits 80 through 80I, respectively, with direct current voltages V_B through V_K , respectively, corresponding to scaling factors pertaining to particular constituents. By way of example, voltages V_B through V_K may correspond to values of 0.02, 0.2, 1.0, 0.2, 0.15, 0.02, 0.2, 0.1, 0.02 and 0.1 volts, respectively. Sample and hold circuits 85 through 85I are controlled by pulse E_K to sample and hold the outputs from multipliers 84 through 84I.

The signals from circuits 85F through 85I are summed by summing means 90 which provides a signal corresponding to the olefins in the olefin-isoparaffin stream in line 6. A divider 93 divides the output from

sample and hold circuit 85F with the signal from summing means 90 to provide a signal E_{15} corresponding to the ratio P_B of propylene to olefins.

Summing means 95 sums the outputs from sample and hold circuits 85 through 85I to provide a signal corresponding to the total constituents of the olefin-isoparaffin stream. A divider 96 divides the signal from summing means 90 with the signal from summing means 95 to provide a signal E_{16} corresponding to the ratio of olefins to the total constituents of the stream in line 6.

Referring back to FIG. 1, signal E_{16} from olefin signal means 60 is multiplied with olefin-isoparaffin flow rate signal E_3 by a multiplier 100 to provide a signal E_{17} corresponding to the flow rate R_o of olefins in line 6.

A signal E_{18} corresponding to the percent volume P_K of alkylate in the hydrocarbon product is derived in a manner similar to the generation of signal E_{15} . Chromatograph means 55A periodically samples the hydrocarbon product in response to reset pulse E_{10} . Chromatograph means 55A provides signal E_{11A} to alkylate signal means 105 and a pulse signal E_{12A} to programmer 58.

Referring again to FIG. 3, pulse signal E_{12A} is applied to a control pulse circuit 74A which in turn provides control pulses E_{4A} through E_{4A} . One shot multivibrators 75A and 76A are responsive to control pulse E_{4A} to provide control pulse E_{KA} .

Referring to FIGS. 1 and 4, control pulses E_{4A} through E_{4A} are provided to alkylate signal means 105 which is similar to olefin signal means 60. It can be appreciated that a repetition of the details of signal means 60 would be cumbersome. It is sufficient to say that alkylate signal means 105 differs from olefin means 60 in that summing means 90 and divider 93 are not present in alkylate signal means 105. Alkylate signal means 105 further differs in that the output from sample and hold circuit 85I, corresponding to the constituent having 6 or more carbon atoms, is applied to divider 96 in place of the output from the deleted summing means 90 so that divider 96 in alkylate signal means 105 provides signal E_{18} .

Referring now to FIGS. 1 and 5, H_C computer 110 receives signal E_9 from H_B computer 45 and provides signals E_{19} , E_{20} corresponding to the terms H_{C1} and H_{C2} , respectively in the aforementioned equations. Signal E_9 is applied to summing means 112 and to subtracting means 113 which also receive a direct current voltage V_4 corresponding to the predetermined change ΔH in the hydrocarbon content of the recycle acid. Summing means 112 adds voltage V_4 and signal E_9 to provide a signal corresponding to an increased hydrocarbon content while subtracting means 113 subtracts voltage V_4 from signal E_9 to provide a signal corresponding to a decreased hydrocarbon content. The signals from means 112 and 113 are applied to comparators 114, 114A along with direct current voltages V_5 and V_6 , respectively. Voltages V_5 , V_6 correspond to an upper limit and a lower limit, H_{C1} and H_{C2} , respectively, for the recycle acid hydrocarbon content.

Comparator 114 provides a high level direct current output when the signal from summing means 112 is not more positive than voltage V_5 and a low level output when the signal from summing means 112 is more positive than voltage V_5 . The output from comparator 114 controls an electronic switch receiving the signal from

summing means 112 and signal E_9 . When the increased hydrocarbon content signal exceeds the upper limit for the hydrocarbon content, the low level output from comparator 114 causes electronic switch 116 to pass signal E_9 as the H_{C1} signal E_{19} . When the increased hydrocarbon content signal is not more positive than voltage V_5 , switch 116 is controlled to pass the signal from summing means 112 as the H_{C1} signal E_{19} .

Comparator 114A and switch 116A cooperate in a similar manner, using the signal from subtracting means 113 and voltage V_6 . Comparator 114A provides a high level direct current output when voltage V_6 is more negative than signal E_9 and a low level output when voltage V_6 is not more negative than signal E_9 . Switch 116A passes the signal from subtracting means 113 as a signal E_{20} when comparator 114A provides a low level output and signal E_9 as signal E_{20} when comparator 114A provides a high level output.

Changes in earnings ΔE_{A1} and ΔE_{A2} , for an increased hydrocarbon content and for a decreased hydrocarbon content, respectively, are computed. A target hydrocarbon content is determined from the computation. In FIG. 1, signals E_9 , E_4 , E_5 , E_1 , E_{15} , E_{17} and E_{18} are applied to computers 130, 130A. Computer 130 provides a signal E_{21} corresponding to the change ΔE_{A1} in earnings resulting from an increased hydrocarbon content in accordance with the received signals and signal E_{19} from H_C computer 110 and equation 1.

Referring now to FIG. 6, a comparator 133 in computer 130 compares signal E_{15} with a direct current voltage V_7 corresponding to an upper limit P_L for the ratio of propylene to olefins. When voltage V_7 is more negative than signal E_{15} , comparator 133 provides a high level direct current output to an electronic switch 134, when voltage V_7 is not more negative than signal E_{15} , the output from comparator 133 goes to a low level. Signal E_{15} , voltage V_7 are also applied to a divider 135 which divides signal E_{15} with voltage V_7 to provide a signal corresponding to the ratio of P_B/P_U . The signal from divider 135 is applied to electronic switch 134 which also receives a direct current voltage V_8 , corresponding to 1.0. Electronic switch 134 passes the signal from divider 135 when the output from comparator 133 is at a low level as a signal E_{22} and voltage V_8 as signal E_{22} when the output from comparator 133 is at a high level. Signal E_{22} is provided to G computers 138, 138A which also receives signals E_9 and E_{19} , respectively.

Signals E_4 , E_5 and E_{17} are applied to S computers 140, 140A. S computer 140 receives signal E_9 while S computer 140A receives signal E_{19} . S computers 140, 140A provide signals E_{23} and E_{24} , respectively, corresponding to the terms S_B and S_C , respectively, to G computers 138 and 138A, respectively. Referring to FIG. 7, signals E_4 , E_5 are summed by summing means 142, in computer 140, to provide a signal corresponding to the term R_R+R_H . A multiplier 143 multiplies the signal from 142 with signal E_{17} to provide a signal to a multiplier 144. Multiplier 144 multiplies the signal from multiplier 143 with voltage V_1 to provide a signal corresponding to the numerator in equation 8. Subtracting means 148 subtracts signal E_9 from voltage V_1 to provide a signal corresponding to the term $(100-H_B)$ to a multiplier 149 where the signal from subtracting means 148 is multiplied with signal E_4 . A multiplier 150 multiplies the signal from multiplier 149 with the direct current voltage V_9 , corresponding to the term C_V , to pro-

vide a signal corresponding to denominator of equation 8. A divider 151 divides the signal from multiplier 144 with the signal from multiplier 150 to provide signal E₂₃.

Computer 140A is similar to computer 140 except that signal E₁₉ is used in lieu of signal E₉ to provide signal E₂₄.

Referring now to FIG. 8, a multiplier 158 in G computer 138 squares signal E₂₃ to provide a signal corresponding to the term S² in equation 5. A multiplier 159 multiplies the signal from multiplier 158 with a direct current voltage V₁₀, corresponding to the term a₁ in equation 5, to provide a signal to summing means 160. A multiplier 163 multiplies signals E₂₂, E₉ together to provide a signal corresponding to P_RH_R to another multiplier 164. Multiplier 164 multiplies the signal from multiplier 163 with a direct current voltage V₁₁, corresponding to the term a₂. Summing means 160 sums the outputs from multipliers 159, 164 to provide a signal E₂₅ corresponding to the quantity G_B.

G computer 138A is similar to computer 138 except that computer 138A provides signal E₂₆ instead of signal E₂₅ and uses signal E₁₉ in lieu of signal E₉.

Referring again to FIG. 6, subtracting means 170 subtracts signal E₂₅ from signal E₂₆ to provide a signal E₂₇ corresponding to the term ΔQ . A multiplier 171 multiplies signal E₂₇ with a direct current voltage V₁₂ corresponding to the economic value W_Q in equation 1 to provide a signal E₂₈.

F_S computers 175 and 175A receive signals E₁₅, E₂₃ and E₁₅, E₂₄, respectively, to provide signals E₂₉ and E₃₀, respectively. Signals E₂₉ and E₃₀ correspond to the terms F_{SB} and F_{SC} in equation 10.

Referring now to FIG. 9, signal E₂₃ is squared by multiplier 177 to provide a signal corresponding to the term S_B². A voltage V₁₃ corresponding to the mathematical constant e is applied to a conventional type logarithmic amplifier 178 which provides a signal corresponding to log e. A multiplier 179 multiplies the signal from multiplier 177 with the signal from amplifier 178 to provide a signal corresponding to the term S₂ log e. Subtracting means 184 subtracts signal E₁₅ from voltage V₈ to provide a signal corresponding to the term (1-P_B) in the equation 16. A divider 185 divides signal E₁₅ with the signal from subtracting means 184 to provide a signal corresponding to the term P_B/(1-P_B). Multipliers 186, 187 and 188 cooperate to raise the signal from multiplier 185 to powers of 2, 3 and 4 so that multipliers 186, 187, 188 provide signals corresponding to the terms [P_B]²/(1-P_B), [P_B]³/(1-P_B) and [P_B]⁴/(1-P_B), respectively. Multipliers 190 through 193 multiply the signals from divider 185 and multipliers 186, 187, 188 with direct current voltages V₁₄, V₁₅, V₁₆ and V₁₇, respectively, corresponding to the terms d₁, d₂, d₃ and d₄, respectively, in equation 16. Summing means 200 sums the outputs from multipliers 190 through 193. A multiplier 201 multiplies the output from summing means 200 with the signal from multiplier 179 to provide a signal to an antilog circuit comprising an operation amplifier 202 with a function generator 203 as a feedback element. Function generator 203 may be of the type manufactured by Electronic Associates as their part number PC-12. Operational amplifier 202 provides signal E₂₉ corresponding to the term F_{SB}.

Referring again to FIG. 6, F_S computer 175A is similar to computer 175 except that signal E₂₄ is used in lieu of signal E₂₃.

A divider 210 divides signal E₃₀ with signal E₂₉ to provide a signal E₃₁ corresponding to the term F_{SC}/F_{SB}.

An F_H computer 215 receives signal E₉ and provides a signal E₃₂ corresponding to one value for the term F_{HB}. Referring also to FIG. 10, there is shown F_H computer 215 which includes subtracting means 217 subtracting a direct current voltage V₁₈, corresponding to a reference hydrocarbon content H_R, from signal E₉ to provide a signal corresponding to the term H_B-H_R. A divider divides the signal from subtracting means 217 with voltage V₁ to provide a signal corresponding to the term (H_B-H_R)/100. Multipliers 220 and 221 raise the last mentioned term to the powers of 2 and 3. Multipliers 222, 223 and 224 multiply the signals from divider 218 and multipliers 220 and 221, respectively, with direct current voltage V₁₉, V₂₀ and V₂₁, respectively. Voltage V₁₉, V₂₀ and V₂₁ correspond to terms C₃, C₄ and C₅, respectively, in Equation 13. Summing means 225 sums the signals from multipliers 222, 223 and 224 with a direct current voltage V₂₂ corresponding to the constant C₂ to provide signal E₃₂.

F_H computer 215A is similar to computer 215 except that signal E₁₉ is used in place of signal E₉. Computer 215A provides signal E₃₃ corresponding to one value for the F_{HC}.

As indicated in the equations, the one value for F_{HB}, as represented by signal E₃₂, is used if a certain condition exists. The necessary condition is that hydrocarbon content H_B must be less than an upper limit H_M for the hydrocarbon content. Referring back to FIG. 6, a comparator 230 compares signal E₉ with a direct current voltage V₂₃, corresponding to H_M to provide an output to electronic switch 231. Comparator 230 provides a low level output when signal E₉ is not more negative than voltage V₂₃ and a high level output when signal E₉ is more negative than voltage V₂₃. Electronic switch 231 receives signal E₃₂ and a direct voltage V₂₄, corresponding to the term C₁. When comparator 230 provides a high level output, switch 231 passes signal E₃₂ as signal E₃₄ corresponding to the term F_{HB}. When the hydrocarbon content H_B is not less than the upper limit hydrocarbon content H_M, comparator 230 provides a low level output causing electronic switch 231 to pass voltage V₂₄ as signal E₃₄. In a similar manner, comparator 230A and electronic switch 231A cooperate to compare signal E₁₉, corresponding to the hydrocarbon content H_C, with voltage V₂₃, corresponding to H_M, so that signal E₃₃, corresponding to the one value of F_{HC}, is passed as signal E₃₅ when the hydrocarbon content is less than the upper limit H_M, and voltage V₂₄, corresponding to the term C₁, is passed as signal E₃₅ when the hydrocarbon content H_C is not less than the upper limit H_M.

A divider 235 divides signal E₃₄ with signal E₃₅ to provide a signal E₃₆ corresponding to the term F_{HB}/F_{HC}. A multiplier 236 multiplies signals E₃₁, E₃₆ to provide a signal to subtracting means 237. Subtracting means 237 subtracts voltage V₈ from multiplier 236 to provide a signal corresponding to the term (F_{SC}F_{HB} - 1/F_{SB}F_{HC}).

A multiplier 240 multiplies signals E₅, E₁₈ to provide a signal corresponding to the term R_HP_K. Another multiplier 241 multiplies signal E₁ with a direct current voltage V₂₅ corresponding to the constant b to provide

a signal corresponding to the term bR_{AB} , to divider 242. Divider 242 divides the signal from multiplier 241 with the signal from multiplier 240 to provide a signal corresponding to the acid consumption A_B . A multiplier 243 multiplies the output from subtracting means 237 with the signal from divider 242 to provide a signal E_{37} corresponding to the term ΔA . A multiplier 244 multiplies signal E_{37} with a direct current voltage V_{26} corresponding to the term W_A to provide a signal E_{38} . Subtracting means 250 subtracts signal E_{38} from signal E_{28} to provide signal E_{21} .

ΔEA computer 130A operates in a similar manner to provide signal E_{21A} , the difference being that signal E_{20} is used in computer 130A wherever signal E_{19} is used in computer 130 so that signal E_{21A} corresponds to the change in earnings to a decrease in hydrocarbon content.

Referring to FIGS. 1 and 11, signals E_{21} , E_{21A} from computers 130 and 130A, respectively, are applied to target hydrocarbon content H_T signal means 251, along with signals E_9 , E_{19} and E_{20} . H_T signal means 251 is essentially a selective switch for passing the H_{C1} , H_{C2} or H_R signal as the target recycle acid hydrocarbon content signal E_{40} . In signal means 251, comparators 252 and 252A compare signals E_{21} and E_{21A} , respectively, with a zero reference potential, such as ground. While another comparator 252B compares signals E_{21} , E_{21A} with each other. For the condition that the ΔEA_1 earning is positive and is more positive than the ΔEA_2 , signal means 251 provides the H_{C1} signal E_{19} as the H_T signal E_{40} . For this condition, comparators 252 and 252B provide high level outputs which enable an AND gate 253 causing AND gate 253 to provide a high level output. The high level output from AND gate 253 renders an electronic switch 254 conductive to pass signal E_{19} as signal E_{40} . The output from AND gate 253 is inverted to a low level output by an inverter 255 which disables another AND gate 256. When disabled, AND gate 256 provides a low level output which renders an electronic switch 254A receiving signal E_9 non-conductive, thereby blocking signal E_9 . The high level output from comparator 252B is inverted to a low level output by an inverter 257 causing another AND gate 258 to provide a low level output to another electronic switch 254B. Switch 254B is rendered non-conductive by the low level output and blocks signal E_{20} .

For the condition that signal E_{21A} is positive and is more positive than signal E_{21} , comparators 252A and 252B provide a high level and a low level output, respectively. Inverter 257 inverts the output from comparator 252B to a high level so that AND gate 258 receiving two high level signals provides a high level output to switch 254B. Switch 254B passes signal E_{20} as signal E_{40} in response to the high level output from AND gate 258. The output from comparator 252B causes AND gate 253 to provide a low level output to switch 254 causing switch 254 to block signal E_{19} . The high level output from AND gate 258 is inverted to a low level by an inverter 259 which causes AND gate 256 to provide a low level output to switch 254A. Switch 254A blocks signal E_9 in response to the low level output from AND gate 256.

For the condition that signals E_{21} , E_{22} are negative, comparators 252, 252A provide low level outputs to AND gates 253 and 258, respectively, causing them to provide low level outputs. Inverters 255, 259 invert the

low level outputs to high levels causing AND gate 256 to provide a high level output rendering switch 254A conductive. When rendered conductive, switch 254A passes signal E_9 as signal E_{40} . The low level outputs from AND gates 253, 258 render switches 254 and 254B, respectively, non-conductive to block signals E_{19} and E_{20} , respectively.

Referring now to FIGS. 1, 3 and 12, H_T signal means 251 provides signal E_{40} to set point signal means 270 which also receives signals E_2 , E_9 , E_{13} and E_{14} . Set point signal means 270 provides a signal E_{41} for adjusting the set point of level recorder controller 34. Subtracting means 271 subtracts signal E_{40} from signal E_9 to provide a signal corresponding to the expression $(H_B - H_T)$ in the following equation:

$$\Delta L_D = k(H_B - H_T)$$

22.

where ΔL_D is a calculated desired change in the interface level of settler 12 due to the new target hydrocarbon content and k is a constant. By way of example k may have a value of 0.5.

A multiplier 272 multiplies the signal from subtracting means 271 with a direct current voltage V_{30} , corresponding to the term k in equation 22, to provide a signal E_{42} which corresponds to the desired change in interface level ΔL_D when the target hydrocarbon content is changed. However, there are limitations on the interface level change allowed during one cycle of operation. A selector circuit 273 receives signal E_{42} from multiplier 272 and direct current voltages V_{31} , V_{32} corresponding to an upper limit change ΔL_U and a lower limit change ΔL_L for the interface level. Selector circuit 273 includes comparators 275 and 275A which compare the signal E_{42} with voltages V_{31} and V_{32} , respectively.

For the condition that the desired change ΔL_D is within the limits, comparators 275 and 275A provide high level outputs causing an AND gate 280 to provide a high level output. The high level output from AND gate 280 renders an electronic switch 281 conductive to pass signal E_{42} as signal E_{43} , the selected change in interface level ΔL_S . The high level outputs from comparators 275, 275A are inverted to low levels by the inverters 283, 283A to render electronic switches 281A and 281B, respectively, non-conductive to block voltages V_{31} and V_{32} , respectively.

For the conditions that ΔL_D exceeds the upper limit ΔL_U , comparators 275 and 275A provide a low level output and high level output, respectively. Inverter 283 inverts the low level output from comparator 275 to a high level to enable switch 281A to pass voltage V_{31} as ΔL_S signal E_{43} . AND gate 280 provides a low level output in response to the low level output from comparator 275 to render switch 281 non-conductive thereby blocking signal E_{42} . The high level output from comparator 275A is inverted to a low level by inverter 283A to render switch 281B non-conductive thereby blocking voltage V_{32} .

For the condition that the interface level change ΔL_D exceeds the lower limit ΔL_L , comparators 275, 275A provide a high level and a low level output, respectively. Switch 281 is rendered non-conductive to block signal E_{42} by a low level output from AND gate 280 in response to the low level output from comparator 275A. The high level output from comparator 275 is

inverted to a low level by inverter 283 to render switch 281A non-conductive thereby blocking voltage V_{31} . The output from comparator 275A is converted to a high level by inverter 283A rendering switch 281B conductive to pass voltage V_{32} as ΔL_s to signal E_{43} .

Summing means 285 sums signal E_{43} and E_2 to provide a signal E_{44} corresponding to a calculated desired interface level L_D . Selector circuit 273A, which is similar to circuit 273, compares signal E_{44} with direct current voltages V_{33} and V_{34} , corresponding to an upper limit L_U and a lower limit L_L , respectively, for the interface level in settler 12. Selector circuit 273A provides signal E_{44} as the selected interface level L_s signal E_{45} when the calculated interface level L_D is within the limits defined by L_U and L_L . Selector circuit 273A provides voltage V_{33} as signal E_{45} , when the calculated interface level L_D exceeds the upper limit L_U and provides voltage V_{34} as signal E_{45} when the calculated interface level L_D exceeds the lower limit L_L .

Signal E_{45} is applied to a sample and hold circuit 289 and to an electronic switch 290. Pulse E_{13} from programmer 58 causes sample and hold circuit 289 to sample and hold signal E_{45} . Sample and hold circuit 289 prevents calculations for a new value of signal E_{45} from adversely affecting the alkylation unit until such time as the calculation is complete.

Signal E_{45} normally passes through electronic switch 290 to become signal E_{41} , which positions the set point of level recorder controller 34. However, during calculations, switch 290 passes the output from sample and hold circuit 289 as signal E_{41} in response to pulse E_{14} . It can be determined from FIG. 3 that pulse E_{13} occurs before pulse 14. The pulse E_{14} is of suitable width so as to terminate after the calculations.

The system of the present invention determines a desirable value for the hydrocarbon content for the recycle acid in an alkylation unit and controls the hydrocarbon content of the recycle acid to maintain it at the desirable value.

Although the present invention is shown using analog computers, it would be obvious to one skilled in the art that signals E_1 through E_8 , E_{15} and E_{18} may be converted to digital signals and a general purpose digital computer may be programmed to provide the control function as taught by the present invention. Naturally, the output from the digital computer may be converted to analog signal such as signal E_{41} .

What is claimed is:

1. A system for controlling an alkylation unit to achieve a desired hydrocarbon content in recycle acid, said alkylation unit includes a contactor wherein olefins-isoparaffin entering the contactor are contacted in the presence of acid and said contactor provides an acid-hydrocarbon mixture to a settler which separates the acid to provide a hydrocarbon product, including alkylate, and hydrocarbon enriched acid, a portion of the enriched acid is discharged, fresh acid is added to the remaining enriched acid which is then provided to the contactor as recycle acid, comprising means for controlling one flow rate of the fresh acid and discharge acid flow rates relative to the other flow rate in accordance with a control signal; means for sensing characteristics of the olefins-isoparaffin, the fresh acid, the recycle acid and the hydrocarbon product and providing signals corresponding thereto; means for sensing the flow rates of the olefins-isoparaffin, the recycle acid, the discharge acid and the hydrocarbon product and

providing corresponding signals; means for sensing the interface level in the settler and providing a signal representative thereof; means for providing signals W_Q and W_A corresponding to economic values related to the octane rating of the alkylate and to the cost of the acid, respectively; and means connected to all of the other means for providing the control signal to the control means in accordance with the characteristic signals, the flow rate signals, the level signal and the economic signals to control the one acid flow rate so as to control the interface level to achieve the desired hydrocarbon content in the recycle acid, and said control signal means includes means connected to the characteristics sensing means for providing a signal corresponding to the hydrocarbon content H_B of the recycle acid in accordance with the characteristic signals; means connected to the H_B signal means for providing signals corresponding to an increased hydrocarbon content H_{C1} for the recycle acid and for a decreased hydrocarbon content H_{C2} for the recycle acid; means connected to the H_B signal means and to the $H_{C1}-H_{C2}$ signal means for providing signals corresponding to a change in earnings ΔEA_1 for an increased hydrocarbon content condition and ΔEA_2 for a decreased hydrocarbon content condition in accordance with the H_B , H_{C1} and H_{C2} signals, and means connected to the H_B signal means, to the $H_{C1}-H_{C2}$ signal means and to the earnings change signal means for selecting the H_B , H_{C1} or H_{C2} signal in accordance with the ΔEA_1 and ΔEA_2 signals as a desired hydrocarbon content condition and for providing a signal corresponding thereto as the control signal.

2. A system as described in claim 1 in which the earnings change signal means includes ΔQ signal means for providing signals corresponding to a change in octane rating ΔQ_1 for the increased hydrocarbon condition and to a change in octane rating ΔQ_2 for the decreased hydrocarbon condition, ΔA signal means for providing signals corresponding to a change in acid consumption ΔA_1 for the increased hydrocarbon content condition and to a change in acid consumption ΔA_2 for the decreased hydrocarbon condition, and means connected to the economic value signal means, to the octane change signal means and to the acid consumption change signal means for providing the ΔEA_1 and ΔEA_2 signals in accordance with the following equation:

$$\Delta EA = (\Delta Q)(W_Q) - (\Delta A)(W_A)$$

where the ΔEA_1 signal is derived by using the ΔQ_1 and ΔA_1 signals, where ΔQ_1 and ΔA_1 are substituted for ΔQ and ΔA , respectively, and the ΔEA_2 signal is derived by using the ΔQ_2 and ΔA_2 signals, where ΔQ_2 and ΔA_2 replace ΔQ and ΔA , respectively.

3. A system as described in claim 2 in which the ΔQ signal means includes G signal means for providing signals corresponding to a quantity G_{C1} for the increased hydrocarbon content condition, to a quantity G_{C2} for a decreased hydrocarbon content condition and to a quantity G_B for the existing hydrocarbon content condition, and means connected to the G signal means for providing the ΔQ_1 and ΔQ_2 signals in accordance with the G_{C1} , G_{C2} and G_B signals and the following equation:

$$\Delta Q = G_C - G_B$$

where the ΔQ_1 signal is developed by using the G_{C1} and G_B signals, where G_{C1} is substituted for G_C and the ΔQ_2 is generated by using the G_{C2} and G_B signals, where G_{C2} is substituted for G_C in the last mentioned equation.

4. A system as described in claim 3 in which the ΔA signal means includes means for providing a signal corresponding to the existing acid consumption A_B , F_S signal means for providing signals corresponding to the quantities F_{SB} , F_{SC1} and F_{SC2} for the existing hydrocarbon content condition, the increased hydrocarbon content condition, and the decreased hydrocarbon content condition, respectively, F_H signal means for providing signals corresponding to the quantities F_{HB} , F_{HC1} and F_{HC2} for the existing hydrocarbon content condition, the increased hydrocarbon content condition, and the decreased hydrocarbon content condition, respectively, and means connected to the acid consumption signal means, to the F_S signal means, to the F_H signal means for providing signals corresponding to ΔA_1 and to ΔA_2 in accordance with the A_B , F_S , F_{HB} , F_{SB} and F_{HC} signals and the following equation:

$$\Delta A = A_B [(F_{SC} F_{NB} / F_{SB} F_{HC}) - 1]$$

where the ΔA_1 signal is generated using the F_{SC1} and F_{HC1} signals, where F_{SC1} and F_{HC1} are substituted for F_{SC} and F_{HC} , respectively, and the ΔA_2 signal is generated using the F_{SC2} and F_{HC2} signals, where F_{SC2} and F_{HC2} replace F_{SC} and F_{HC} , respectively.

5. A system as described in claim 4 in which the A_B signal means includes means for providing a signal corresponding to a constant b , means connected to the characteristic sensing means for providing a signal corresponding to the volume fraction P_k of alkylate in the hydrocarbon product, and means connected to the flow rate sensing means for providing the A_B signal in accordance with the following equation:

$$A_B = b(R_{AB})/P_k R_H$$

where R_{AB} is the other flow rate of the fresh acid and discharge acid flow rates and R_H is the flow rate of the hydrocarbon product.

6. A system as described in claim 5 in which the G signal means includes means for providing signals corresponding to constants a_1 and a_2 ; means for providing a signal corresponding to a quantity P_R ; S signal means for providing signals corresponding to quantities S_B , S_1 and S_2 for the existing hydrocarbon content condition, the increased hydrocarbon content condition and the decreased hydrocarbon content condition, respectively, and means connected to the a_1-a_2 , P_R , S , H_B , $H_{C1}-H_{C2}$ signal means for providing the G_B , G_{C1} and G_{C2} signals in accordance with the a_1 , a_2 , P_R , S_B , S_1 , S_2 , H_B , H_{C1} and H_{C2} signals and the following equation:

$$G = a_1 S^2 + a_2 P_R H$$

where the G_B signal is developed using the S_B and H_B signals, where S_B and H_B are substituted for S and H , respectively, the G_{C1} signal is developed using the S_1 and H_{C1} signals, where S_1 and H_{C1} are substituted for S and H , respectively, and the G_{C2} signal is developed using the S_2 and H_{C2} signals, where S_2 and H_{C2} are substituted for S and H , respectively.

7. A system as described in claim 6 in which one of the signals provided by the characteristic sensing means corresponds to the ratio P_B of propylene to ole-

fins; and the P_R signals means includes means for providing a signal corresponding to an upper limit P_U for the ratio of propylene to olefins, means connected to the characteristic sensing means and to the P_U signal for comparing the P_B and P_U signals, means connected to the characteristic signal means and to the P_R signal means for providing a signal corresponding to P_B/P_U , means for providing a signal corresponding to 1.0, and switching means controlled by the comparing means to pass the 1.0 signal as the P_R signal while blocking the P_B/P_U signal when the ratio P_B is equal to or greater than the limit ratio P_U and to pass the P_B/P_U signal as the P_R signal while blocking the 1.0 signal when the ratio P_B is less than the limit ratio P_U .

8. A system as described in claim 7 in which the S signal means includes means for providing a signal corresponding to the volume C_V of the contactor, means connected to the characteristic sensing means and to the flow rate sensing means for providing a signal corresponding to the flow rate R_o of the olefins in accordance with the characteristic signals and the olefin-isoparaffin flow rate signal, means connected to the C_V signal means, to the R_o signal means, to the H_B signal means, to the flow rate sensing means, and to the $H_{C1}-H_{C2}$ signal means for providing the S_B , S_1 and S_2 signals in accordance with the R_o , C_V , H_B , H_{C1} and H_{C2} signals, the flow rate signals and the following equation:

$$S = 100R_o (R_R + R_H) / C_V R_R (100 - H)$$

where R_R and R_H are the flow rates of the recycle acid and hydrocarbon product, respectively, the S_B , S_1 and S_2 signals are developed using the H_B , H_{C1} and H_{C2} , respectively, where S_B , S_1 and S_2 are substituted for H in the last mentioned equation.

9. A system as described in claim 8 further comprising means for providing a signal corresponding to the upper limit H_M for the hydrocarbon content; and in which the F_H signal means includes means connected to the H_B signal means and to H_M signal means for comparing the H_B signal with the H_M signal, means for providing signals corresponding to constants C_1 through C_5 , means for providing a signal corresponding to a reference hydrocarbon content H_R for the recycle acid, means connected to the C_1-C_5 signal means, to the H_B signal means, to the $H_{C1}-H_{C2}$ signal means and to H_R signal means for providing signals corresponding to F_{HB} , F_{HC1} and F_{HC2} in accordance with the C_2 through C_5 signals and the H_B , H_{C1} , H_{C2} and H_R signals and the following equation:

$$F_H' = C_2 + C_3 [(H - H_R) / 100] + C_4 [(H - H_R) / 100]^2 + C_5 [(H - H_R) / 100]^3$$

where the F'_{HB} , F'_{HC1} and F'_{HC2} signals are derived using the H_B , H_{C1} and H_{C2} signals where F_{HB} , F_{HC1} and F_{HC2} are substituted for H , respectively, in the last mentioned equation, and switching means connected to the last mentioned comparing means, to the C_1-C_5 signal means and to F'_{HB} , F'_{HC1} and F'_{HC2} signal means and controlled by the last mentioned comparing means to provide the C_1 signal as the F_{HB} , F_{HC1} and F_{HC2} signals while blocking the F'_{HB} , F'_{HC1} and F'_{HC2} signals when the existing hydrocarbon content H_B is not less than the upper limit H_M to the hydrocarbon content and to provide the F'_{HB} , F'_{HC1} and F'_{HC2} signals as the F_{HB} , F_{HC1} and F_{HC2} signals, respectively, while blocking the C_1

signal when the existing hydrocarbon content H_B is less than the upper limit H_M hydrocarbon content.

10. A system as described in claim 9 in which the F_S signal means includes means for providing signals corresponding to constants d_1 through d_4 , and means connected to the P_B signal means, to the d_1-d_4 signal means and the S signal means for providing the signals corresponding to the quantities F_{SB} , F_{SC1} and F_{SC2} in accordance with the S_B , S_1 , S_2 , d_1 through d_4 and P_B signals and the following equation:

$$F_S = \exp \left\{ S^2 \left[d_1 \left(\frac{P_B}{1-P_B} \right) + d_2 \left(\frac{P_B}{1-P_B} \right)^2 + d_3 \left(\frac{P_B}{1-P_B} \right)^3 + d_4 \left(\frac{P_B}{1-P_B} \right)^4 \right] \right\}$$

where the F_{SB} , F_{SC1} and F_{SC2} signals are obtained by using S_B , S_1 and S_2 signals, respectively, where S_B , S_1 and S_2 are substituted for S in the last mentioned equation.

11. A system as described in claim 1 in which the control signal means is a digital computer programmed in a predetermined manner to provide the control signals.

12. A system as described in claim 11 in which the computer has been programmed to determine changes ΔEA_1 and ΔEA_2 in earnings for an increased hydrocarbon content H_{C1} for the recycle acid and a decreased hydrocarbon content H_{C2} for the recycle acid in accordance with the following equations:

$$\Delta EA_1 = (\Delta Q_1) (W_Q) = (\Delta A_1) (W_A)$$

$$\Delta EA_2 = (\Delta Q_2) (W_Q) = (\Delta A_2) (W_A)$$

where ΔQ_1 and ΔQ_2 are changes in the octane ratings for the increased and decreased hydrocarbon content conditions, respectively, ΔA_1 and ΔA_2 are changes in the acid consumption for the increased and decreased hydrocarbon content conditions, respectively, and W_Q and W_A are economic values associated with the octane rating and the acid.

13. A method for controlling an alkylation unit to achieve a desired hydrocarbon content in recycle acid, said alkylation unit includes a contactor wherein olefins-isoparaffin entering the contactor are contacted in the presence of acid and said contactor provides an acid-hydrocarbon mixture to a settler which separates the acid to provide a hydrocarbon product, including alkylate, and hydrocarbon enriched acid, a portion of the enriched acid is discharged, fresh acid is added to the remaining enriched acid which is then provided to the contactor as recycle acid, which comprises controlling one flow rate of the fresh acid and discharge acid flow rates relative to the other flow rate in accordance with a control signal; sensing characteristics of the olefins-isoparaffin, the fresh acid, the recycle acid and the hydrocarbon product; providing signals corresponding to the sensed characteristics; sensing the flow rates of the olefins-isoparaffin, the recycle acid, the discharge acid and the hydrocarbon product; providing signals corresponding to the sensed flow rates; sensing the interface level in the settler; providing a signal representative of the sensed interface level; providing signals W_Q and W_A corresponding to economic values related to the octane rating of the alkylate and to the cost of the acid, respectively; and providing the control signal in accordance with the characteristic signals, the flow rate signals, the level signal and the economic signals to control the one acid flow rate so as to control the in-

terface level to achieve the desired hydrocarbon content in the recycle acid and said control signal step includes providing a signal corresponding to the hydrocarbon content H_B of the recycle acid in accordance with the characteristic signals; providing signals corresponding to an increased hydrocarbon content H_{C1} for the recycle acid and for a decreased hydrocarbon content H_{C2} for the recycle acid; providing signals corresponding to a change in earnings ΔEA_1 for an increased hydrocarbon content condition and ΔEA_2 for a decreased hydrocarbon content condition in accordance with the H_B , H_{C1} and H_{C2} signals, selecting the H_B , H_{C1} or H_{C2} signal in accordance with the ΔEA_1 and ΔEA_2 signals as a desired hydrocarbon content condition, and providing a signal corresponding to the selected signal as the control signal.

14. A method as described in claim 13 in which the earnings change signal step includes providing signals corresponding to a change in octane rating ΔQ for the increased hydrocarbon condition and to a change in octane rating ΔQ_2 for the decreased hydrocarbon condition, providing signals corresponding to a change in acid consumption ΔA_1 for the increased hydrocarbon content condition and to a change in acid consumption ΔA_2 for the decreased hydrocarbon condition, and providing the ΔEA_1 and ΔEA_2 signals in accordance with the following equation:

$$\Delta EA = (\Delta Q) (W_Q) = (\Delta A) (W_A)$$

30 where the ΔEA_1 signal is derived by using the ΔQ_1 and ΔA_1 signals, where ΔQ_1 and ΔA_1 are substituted for ΔQ and ΔA_1 , respectively, and the ΔEA_2 signal is derived by using the ΔQ_2 and ΔA_2 signals, where ΔQ_2 and ΔA_2 are substituted for ΔQ and ΔA , respectively.

35 15. A method as described in claim 14 in which the step for providing ΔQ_1 and ΔQ_2 signals includes providing signals corresponding to a quantity G_{C1} for the increased hydrocarbon content, to a quantity G_{C2} for a decreased hydrocarbon content condition and to a quantity G_B for the existing hydrocarbon content condition, and providing the ΔQ_1 and ΔQ_2 signals in accordance with the G_{C1} , G_{C2} and G_B signals and the following equation:

$$\Delta Q = G_C - G_B$$

45 where the ΔQ_1 signal is developed using the G_{C1} and G_B signals, where G_{C1} is substituted for G_C and the ΔQ_2 signal is developed using the G_{C2} and G_B signals, where G_{C2} is substituted for G_C in the last mentioned equation.

50 16. A method as described in claim 15 in which the step of providing the ΔA_1 and ΔA_2 signals includes providing a signal corresponding to the existing acid consumption A_B , providing signals corresponding to the quantities F_{SB} , F_{SC1} and F_{SC2} for the existing hydrocarbon content condition, the increased hydrocarbon content condition and the decreased hydrocarbon content condition respectively, providing signals corresponding to the quantities F_{HB} , F_{HC1} and F_{HC2} for the existing hydrocarbon content condition, and for the decreased hydrocarbon content condition, respectively, providing the signals corresponding to ΔA_1 and to ΔA_2 in accordance with the A_B , F_{SC} , $F_{HB}F_{SB}$ and F_{HC} signals and the following equation:

$$A = A_B [(F_{SC}F_{HB}/F_{SB}F_{HC}) - 1]$$

55 where the ΔA_1 signal is provided using the F_{SC1} and F_{HC1} signals where F_{SC1} and F_{HC1} are substituted for F_{SC}

and F_{HC} , respectively, and the ΔA_2 signal is developed using the F_{SC2} and F_{HC2} signals where F_{SC2} and G_{HC2} are substituted for F_{SC} and F_{HC} , respectively, in the last mentioned equation.

17. A method as described in claim 16 in which the step of providing the A_B signal includes providing a signal corresponding to a constant b , providing a signal corresponding to the volume fraction P_k of alkylate in the hydrocarbon product, and the A_B signal in accordance with the following equation:

$$A_B = b(R_{AB})/P_k R_H$$

where R_{AB} is the other flow rate of the fresh acid and discharge acid flow rates and R_H is the flow rate of the hydrocarbon product.

18. A method as described in claim 17 in which the step of providing the G_{C1} , G_{C2} and G_B signals includes providing signals corresponding to constants a_1 and a_2 ; providing a signal corresponding to a quantity P_R ; providing signals corresponding to quantities S_B , S_1 and S_2 for the existing hydrocarbon content condition, the increased hydrocarbon content condition and the decreased hydrocarbon content condition, respectively; and providing the G_B , G_1 and G_2 signals in accordance with the a_1 , a_2 , P_R , S_B , S_1 , S_2 , H_B , H_{C1} and H_{C2} signals and the following equation:

$$G = a_1 S^2 + a_2 P_R H$$

where the G_B signal is developed using the S_B and H_B signals, where S_B and H_B are substituted for S and H , respectively, the G_{C1} signal is developed using the S_1 and H_{C1} signals where S_1 and H_{C1} are substituted for S and H , respectively, and the G_{C2} signal is developed using the S_2 and H_{C2} signals, where S_2 and H_{C2} are substituted for S and H , respectively, in the last mentioned equation.

19. A method as described in claim 18 in which one of the characteristic signals provided corresponds to the ratio P_B of propylene to olefins; and the step of providing the P_B signal includes providing a signal corresponding to an upper limit P_U for the ratio of propylene to olefins, comparing the P_B and P_U signals, providing a signal corresponding to P_B/P_U , providing a signal corresponding to 1.0, and providing the 1.0 signal as the P_B signal when the ratio P_B is equal to or greater than the limit ratio P_U and providing the P_B/P_U signal as the P_B signal when the ratio P_B is less than the limit ratio P_U .

20. A method as described in claim 19 in which the step of providing the S signal includes providing a signal corresponding to the volume C_V of the contactor, means connected to the characteristic sensing means and to the flow rate sensing means for providing a signal corresponding to the flow rate R_O of the olefins in

accordance with the characteristic signals and the olefinisoparaffin flow rate signal, providing the S_B , S_1 and S_2 signals in accordance with the R_O , C_V , H_B , H_{C1} and H_2 signals, the flow rate signals and the following equation:

$$S = 100R_O (R_R + R_H)/C_V R_R (100 - H)$$

where R_R and R_H are the flow rates of the recycle acid and hydrocarbon product, respectively, the S_B , S_1 and S_2 signals are developed using the H_B , H_{C1} and H_{C2} signals, respectively, where H_B , H_{C1} and H_{C2} are substituted for H in the last mentioned equation.

21. A method as described in claim 20 further comprising the step of providing a signal corresponding to an upper limit H_M for the hydrocarbon content; and in which the step of providing the F_H signal includes comparing the H_B signal with the H_M signal, providing signals corresponding to constants C_1 through C_5 , providing a signal corresponding to a reference hydrocarbon content H_R for the recycle acid, providing the F_{HC} , F_{HC1} and F_{HC2} signals in accordance with the C_2 through C_5 signals and the H_B , H_{C1} , H_{C2} and H_R signals and the following equation:

$$F_H = C_2 + C_3 [(H - H_R)/100] + C_4 [(H - H_R)/100]^2 + C_5 [(H - H_R)/100]^3$$

where the F_{HB1} , F_{HC1} and F_{HC2} signals are derived using the H_B , H_{C1} and H_{C2} signals, respectively, where H_B , H_{C1} and H_{C2} are substituted for H in the last mentioned equation, providing the C_1 signal as the F_{HB} , F_{HC1} and F_{HC2} signals when the existing hydrocarbon content H_B is not less than the upper limit H_M hydrocarbon content and providing the F_{HB} , F_{HC1} and F_{HC2} signals as the F_{HB} , F_{HC1} and F_{HC2} signals, respectively, when the existing hydrocarbons content H_B is less than the upper limit H_M hydrocarbon content.

22. A method as described in claim 21 in which the step of providing the F_S signal includes providing signals corresponding to constants d_1 through d_4 , and providing the signals corresponding to the quantities F_{SB} , F_{SC1} and F_{SC2} in accordance with the S_B , S_1 , S_2 , d_1 through d_4 and P_B signals and the following equation:

$$45 F_S = \exp \left\{ S^2 \left[d_1 \left(\frac{P_B}{1 - P_B} \right) + d_2 \left(\frac{P_B}{1 - P_B} \right)^2 + d_3 \left(\frac{P_B}{1 - P_B} \right)^3 + d_4 \left(\frac{P_B}{1 - P_B} \right)^4 \right] \right\}$$

where the F_{SB} , F_{SC1} and F_{SC2} signals are obtained by using S_B , S_1 and S_2 signals, respectively, where F_{SB} , F_{SC1} and F_{SC2} are substituted for S in the last mentioned equation.

UNITED STATES PATENT OFFICE
CERTIFICATE OF CORRECTIONPatent No. 3,814,915Dated June 4, 1974Inventor(s) Donald E. Sweeney, Jr.

It is certified that error appears in the above-identified patent and that said Letters Patent are hereby corrected as shown below:

Column 17, line 31: " $\Delta EA_1 = (\Delta Q_1)(W_Q) = (\Delta A_1)(W_A)$ " should read

$-- \Delta EA_1 = (\Delta Q_1)(W_Q) - (\Delta A_1)(W_A) --$

Column 17, line 32: " $\Delta EA_2 = (\Delta Q_2)(W_Q) = (\Delta A_2)(W_A)$ " should read

$-- \Delta EA_2 = (\Delta Q_2)(W_Q) - (\Delta A_2)(W_A) --$

Column 18, line 29: " $\Delta EA = (\Delta Q)(W_Q) = (\Delta A)(W_A)$ " should read

$-- \Delta EA = (\Delta Q)(W_Q) - (\Delta A)(W_A) --$

Signed and sealed this 5th day of November 1974.
